UNITED STATES PATENT OFFICE.

ASA FRANK WHITE, OF CANDOR, NEW YORK, ASSIGNOR OF ONE HALF TO
CHARLES O. WHITE AND EDWARD M. WHITE.

CHAIR.

SPECIFICATION forming part of Letters Patent No. 331,352, dated December 1, 1885.

Application filed September 17, 1884. Serial No. 143,280. (No model.)

To all whom it may concern:

Be it known that I, ASA FRANK WHITE, a citizen of the United States, residing in the town of Candor, Tioga county, New York, have 5 invented an Improved Chair for Household and other uses, of which the following is a specification.

My invention relates to an integral construction of the main parts that compose my chair, 10 said parts being cut from a single piece of wood, and to the joining of the said parts together into a chair, as will be apparent as I describe my chair.

Figure 1 is a side elevation of my chair; Fig. 15 2, a front elevation. Fig. 3 is a view of the piece or block that the posts and legs of the chair are made out of, with a line on its side that shows the saw cleft or cut made partially the length of the piece before it is bent into 20 shape. Fig. 4 is a view of the piece, block, or blank with lines that show the saw clefts or cuts when the blank is designed to furnish the front legs, the back posts, and the back, all made out of one and the same piece of wood, 25 which is still after the chair is made in one piece of wood.

In the figures, *a* is the front leg of one side, and *a'* the front leg of the other side, of the chair; and *b* is one of the corresponding rear 30 posts of the chair. In the blank seen in Fig. 3 there is a line, *c*, which represents a saw-cut, made preferably by a band-saw, cut from its left-hand end toward the right hand, but not quite through the whole length of the 35 blank, leaving the end *b''*, which in the chair becomes the lower end of the rear post, the parts *a* become the front legs, and the part *d* the back, of the chair, as seen in Fig. 1. Two saw-cuts are seen in the block or blank of Fig. 40 4. In that case a small piece, *c''*, is left in the middle, because the blank is longer than is necessary, to allow the front legs, the rear posts, and back to be cut out of the one piece. It is not required for use in the chair, but is in the 45 vision between the ends *a*, and furnishes a convenient entrance-space for the band-saw by the curved lines shown, which lines are continued toward, but not entirely through, each end of the blank, as shown, and, as before 50 said, the left-hand end parts become *a b c*, (seen in Figs. 1 and 2,) and the curved top of the back *d*, Fig. 2, when in the chair. To be

made to assume this shape after being thus cut by the saw the blanks of Fig. 4 are steamed and bent on a form, the art of thus bending wood being one well known and in common use, though the form on which the blank is bent is a special one made to suit my purpose. The same is also true of the steaming and bending of the blank of Fig. 3. In it 55 the ends *a* become when bent the front legs, the middle *c* the arch, and the end *b''* the rear leg end of the rear post, and the part *d* the post and back of the chair.

Two or three ways of utilizing the end *d'*, 60 Fig. 3, are possible: first, to carry up the rear posts straight without a back curving to the height of the back, where they end, then connect their tops by a cross-bar, which is a 65 usual form of joining the posts; second, the two posts of each side or end of the chair may be bent by any suitable curve, similar in its main form to that seen in Fig. 2, and the place of meeting in the middle of the back be joined together; third, the two ends *d'* of the blank 70 of Fig. 3 may be made so long that they shall meet in the middle at or near *d*, Fig. 2, and there be joined by any convenient fixture, and then be continued down to and be made fast 75 in the seat *j* at its rear part.

By a little reflection it will be evident that quite a number of forms of the back of a chair can be made by the various shapes this extended end *d'* can be made to assume, and hence they need not be represented.

The seat *j* is made of solid wood or open cane-work or of perforated wood by any convenient usual form. It is, as shown in the figures, made fast by bolts, rivets, or wood pins to the tops of the arches at *g g' g''*, three places, 80 and to the rear posts at *g''*. At the back there may or may not be an arched piece similar to *e*, Fig. 2. At the place where the saw-clefts end and the arches begin bolts, rivets, or pins 85 better be used, so that the ends of the legs do not split. The usual cross-rods, *f*, connect the legs of the chair to each other; and posts, rods, or spindles are, when desirable, used in the back of the chair, as seen at *i*, Fig. 2. The 90 ends of the blanks are preferably cut lighter than the saw-cuts would leave them, as shown by the secondary cuts *b''*, Fig. 3. The dotted line at *d''* shows that there is in that blank superfluous wood to be cut away. A sand-band 95 100

or other means cuts, rounds, and shapes and polishes the blanks after being bent.

By these means and forms I construct a very strong, useful chair, novel in its principles, as

5 I believe.

Bending parts of chairs is an old art; hence I do not claim that; but

What I do claim is—

10 1. A chair having its back and rear and front legs integral and cut from a single piece of wood.

15 2. A chair having its back and rear and front legs integral and cut from a single piece of wood and curved, as shown, to form side supports for its seat.

3. A chair having its back and rear and

front legs integral and cut from a single piece of wood, the rear and front legs being connected and supported by a curved piece, which also forms a side support for the seat.

20

4. In a chair, the combination of the back and rear and front legs formed integrally and cut from a single blank, the seat, and fastening devices *a b g*, as shown and described.

5. A chair whose rear post and front leg and 25 connecting side arch are integral and cut from a single piece of wood.

ASA FRANK WHITE.
